(57) **CLAIM**

The ornamental design for a phone case, as shown and described.

DESCRIPTION

FIG. 1 is a front, right-side, and top perspective view of a phone case showing my new design with the kickstand in a stowed configuration;

FIG. 2 is a rear, left and bottom perspective view thereof; FIG. 3 is a front, right-side, and top perspective view thereof with the kickstand in an extended configuration;

FIG. 4 is a front view thereof;

FIG. 5 is a rear view thereof;

FIG. 6 is a left side view thereof;

FIG. 7 is a right side view thereof;

FIG. 8 is an enlarged top plan view thereof;

FIG. 9 is an enlarged bottom plan view thereof; and,

FIG. 10 is an enlarged detail view of the delineated region 10 in FIG. 1.

The dot-dash broken lines in FIGS. 1 and 10 delineate a region of the phone case, including claimed subject matter, that is shown on enlarged scale in FIG. 10. The dashed broken lines depict portions of the phone case that form no part of the claimed design. The dot-dash and dashed broken lines form no part of the claimed design.

1 Claim, 10 Drawing Sheets
